UNITED STATES PATENT OFFICE

CARL E. EKLIND AND KENNETH J. TOBIN, OF CHICAGO, ILLINOIS, ASSIGNEES TO
CAMEL COMPANY, OF CHICAGO, ILLINOIS, A CORPORATION OF ILLINOIS

HOUSE-CAR CONSTRUCTION

Application filed May 31, 1929. Serial No. 367,200.

This invention relates to a house car construction and concerns itself with a structure whereby the car door may be mounted and moved at all times in a plane within the 5 car wall, whereby the capacity of the car may be increased.

In the past attempts have been made to provide a car structure in which the door moves within the plane of the outer wall of 10 the car. Such attempts have not succeeded and have proved impracticable for the reason that no proper provision was made for strengthening or reinforcing the car wall adjacent the rear of the door.

15 In the Christy Patent No. 1,068,318, there is shown an attempt to make a door that is flush with the wall of the car and a metal panel adjacent the rear end of the car. This metal panel however is not incorporated in the 20 car wall so as to transmit tension or compression between the sill and top plate and consequently it does not reinforce the car. In the Carpenter Patent No. 1,094,835, there is illustrated another attempt to make a flush 25 car door with a sheet metal in the recess to receive the door. But like Christy, this sheet metal panel is not incorporated in the car wall to take the stresses usually assumed by the bracing.

30 It will be evident that in cases when a flush door is used that moves within the plane of the car the diagonal compression or tension strut must be eliminated. In the prior art no proper provision has been made to take 35 care of these stresses usually assumed by the removed strut.

In order to maintain the capacity of the car or to increase the same according to the construction involving this invention, it is 40 necessary that the thickness of the car walls be decreased over that area over which the door moves. In order to provide a good substantial construction, it is necessary that the necessary decrease in the thickness of the 45 walls of the car should not decrease its strength and rigidity, and is capable of transmitting stresses between the sill and top plate.

According to this invention, a sheet metal panel of appropriate strength and rigidity is incorporated in the car wall in that area

over which the door lies when it is open. This sheet metal panel will impart the proper strength and rigidity to the car wall and at the same time will allow the door to move within the outer plane of the sides of the car. 55

The invention comprises the novel structure and combinations of parts hereinafter described and more particularly pointed out and defined in the appended claims.

In the accompanying drawings which illustrate a preferred embodiment of this invention and in which similar reference numerals refer to similar features in the different views:

Figure 1 is a fragmentary side elevational view of a car involving this invention.

Figure 2 is a sectional view taken upon the line II-II of Figure 1 looking in the direction of the arrows.

Figure 3 is a broken horizontal sectional view of the construction shown in Figure 1 but upon a larger scale.

Figure 4 is a view similar to Figure 3 but illustrating a double sheathed car.

Figure 5 is a view similar to Figure 3 75 but illustrating a modification of a door post construction for a single sheathed car.

Figure 6 is an enlarged and broken vertical sectional view taken upon the line VI-VI of Figure 1 looking in the direction of the 80 arrows.

Figure 7 is an enlarged and broken vertical sectional view taken upon the line VII-VII of Figure 1 looking in the direction of the 85 arrows.

Figure 8 is an interior elevational view of the rigidifying metal panel which forms the recess for containing the door when the same has been moved into its open position.

In referring to the drawings, it will be noted that a car door 1 has been illustrated as supported by rollers 2 traveling upon a track 3 which is secured to the lower sill 4. The door is adapted to roll toward the right as shown in Figure 1. In referring to Figures 3 and 4 it will be noted that the front door post 8 which is made of metal, is provided with an indenture 5 into which the front end of the door is adapted to extend for bringing the door within the plane of the 100

outer surface of the car. It will be noted that the rear door post 9, which is also of metal, is in alignment with the indenture 5. The posts 8 and 9 preferably have wooden fillers 6 and 7 upon their inner sides.

In Figure 4, which illustrates a double sheathed car, a slightly different form of metal post 8a is used at the front end of the door. The rear post 9, in Figure 4, is substantially like the rear post shown in Figure 3. The rear posts 9 in both the single sheathed car as shown in Figure 3 and the double sheathed car as shown in Figure 4 have inwardly offset flanges 9a which extend longitudinally to provide means for attaching sheet metal panel 10. The panel 10 is preferably corrugated in instances where a truss of the Howe type is used in connection with the car. The corrugations may however be dispensed with if a truss of the Pratt type is used in connection with the car. It will be observed that post 9 extends a considerable distance around the rear side of the filler 7 in order to form a recess in the wall of the car where the panel 10 is located.

The rear edge of the panel 10 in Figure 3 is attached to a forwardly extending flange on an intermediate metal post 11 having a filler block 12. In Figure 4 involving the double sheathed car, the panel 10 is also attached to a forwardly extending flange on an intermediate post 11a secured thereto. The flanges on the posts 11 and 11a are in alignment with the attaching flanges 9a on the rear door post.

The manner of attaching the upper edge of the panel 10 is best shown in Figures 7 and 8 and in referring to said figures it will be noted that a Z bar 13 has been attached to the side plate or Z bar 14 upon the inner side thereof and the upper edge of the panel 10 is riveted to the depending flange of said Z bar. The lower end of the panel 10 is secured to the upstanding flange of an angle bar 15 which is secured by means of a horizontal flange to the top of the side sill 4. On account of the offset feature of the panel 10, certain eccentric stresses are produced and to overcome these, suitable reinforcing brackets 17 connect the web of the Z bar 13 with the side plate 14. It will be evident that the panel 10 due to its connection with the side plate and sill will transmit the stresses that were transmitted by the diagonal strut which had to be eliminated and will transmit such stresses between the sill and top plate.

In Figure 5, a slight modification has been illustrated especially with relation to the door posts. In this modified form the front door post 18 is substantially in the form of a T bar having a channel portion 18a for receiving the front end of the door. The rear door post 19 is also substantially in the form of a T bar having a wedge shaped projection 19a for cooperating with a weather strip upon

the rear edge of the door. In this modified form, an intermediate post 21 having a filler 20 and which comes next to the rear door post is provided with longitudinally extending flanges in alignment with the flange of the T bar 19. The sheet metal panel 10 is secured to the flanges of the post 21 and the T bar 19. In this modified form, a wood lining 22 covers the interior surface of the panel 10 so that the interior of the car is substantially flush with the door post. While this wooden lining 22 reduces the width of the car, there are instances where it is desirable to avoid piling lading against a metal surface. The structure shown in Figure 5 might be readily built into certain types of existing cars without disturbing the side plate and side sill arrangement or inside lining.

It will be appreciated that according to this invention, it will be possible to increase the capacity of cars without bringing any part thereof within the line of tunnel clearances. The manner in which this is accomplished in no way decreases the strength or rigidity of the car walls as has been the case in attempts heretofore. Moreover the structure whereby this result is attained is exceedingly simple and can be easily applied to existing cars.

We are aware that many changes may be made and numerous details of construction may be varied through a wide range without departing from the principles of this invention, and we do not therefore purpose limiting the patent granted hereon otherwise than necessitated by the prior art.

We claim as our invention:

1. In a house car having a side plate and side sill, a sliding door within the plane of the side wall of the car, and presented exteriorly thereof in open position, said car having a recess for receiving said door in its open position, and a metal panel secured to said side plate and side sill and forming the wall of said recess.

2. In a house car having a side plate and side sill and a door opening with a rear door post, an intermediate post spaced from said rear door post, said posts having inwardly offset flanges, a sheet metal panel secured to said inwardly offset flanges, said side plate and side sill and forming a portion of the car wall, and a sliding door for closing said opening and movable over said sheet metal panel during its opening movements.

3. In a house car having a side plate and side sill and a door opening with a rear door post, an intermediate post spaced from said rear door post, said posts having inwardly offset flanges, a sheet metal panel secured to said flanges and said side plate and sill and a door mounted to close said door opening and movable over said sheet metal panel.

4. In a house car having a side wall with a

recess within the outer plane of said wall, a metal post at each end of said recess, said posts having inwardly offset flanges, a side plate above said recess and a sill below said recess, a sheet metal panel secured to said flanges, plate and sill for forming a depressed pocket and a door mounted on said car and movable into said recess.

5. In a house car having a doorway, a door mounted upon said car for closing said doorway, said door being presented exteriorly of said car in open position and an inset metal panel at the rear of said doorway over which said door is adapted to move during its opening movement, said metal panel being incorporated in the side wall and capable of transmitting stress from the side plate to the side sill.

6. In a house car having a doorway, a side wall, a side plate and a side sill, a door mounted upon said car for closing said doorway, said door being presented exteriorly of said side wall in open position and an inlet metallic member at the rear of said doorway providing a recess and over which said door is adapted to move during its opening movement, said metallic member being incorporated in the side wall and capable of transmitting stress from the side plate to the side sill.

30. In testimony whereof, we have hereunto subscribed our names at Chicago, Cook County, Illinois.

CARL E. EKLIND.
KENNETH J. TOBIN.
